FIG. 5.

UNITED STATES PATENT OFFICE.

ROBERT F. RINGLE, OF ZELIENOPLE, PENNSYLVANIA, ASSIGNOR TO HERMAN PNEUMATIC MACHINE COMPANY, OF ZELIENOPLE, PENNSYLVANIA, A CORPORATION OF PENNSYLVANIA.

JARRING-MACHINE.

1,054,315.

Specification of Letters Patent. Patented Feb. 25, 1913.

Application filed July 17, 1912. Serial No. 709,958.

To all whom it may concern:

Be it known that I, ROBERT F. RINGLE, a resident of Zelienople, in the county of Butler and State of Pennsylvania, have invented a new and useful Improvement in Jarring-Machines; and I do hereby declare the following to be a full, clear, and exact description thereof.

My invention relates to molding machines and has special reference to the form of sand molding machine known as the jarring type wherein the pattern is placed in a casing or flask and sand placed around the same and this is then jarred by pneumatic means until the sand has attained the required degree of solidity.

The object of my invention is to provide a cheap, simple and efficient form of sand molding machine, which, in addition, to the jarring process will be equipped with the necessary apparatus for squeezing the sand into the flask after the jarring operation is completed and the flask will then be reversed and the pattern removed therefrom by raising the same from said flask.

My invention consists, generally stated, in the novel arrangement, construction and combination of parts as hereinafter more specifically set forth and described and particularly pointed out in the claims.

To enable others skilled in the art to which my invention appertains to construct and use my improved molding machine, I will describe the same more fully referring to the accompanying drawing, in which—

Figure 1 is a side elevation of my improved molding machine complete. Fig. 2 is a like view of the same showing the squeezing operation. Fig. 3 is a similar view showing the machine in position to have the flask reversed for withdrawing the pattern from the same. Fig. 4 is a like view showing the pattern withdrawn from the flask. Fig. 5 is a vertical cross sectional view of the machine in its normal position. Fig. 6 is an end view showing a portion of the molding machine with the pattern flask suspended for reversing.

Like symbols of reference herein indicate like parts in each of the figures of the drawing.

As illustrated in the drawing A represents my improved molding machine in which 1 represents the base above which is a

rectangular casing 2. The casing 2 has a cylinder 3 within the same and at the upper end thereof and such cylinder is located centrally of the walls of said casing and has a series of vertical wings 4 connecting the outer sides of the same with the inner sides of said casing. Within the cylinder 3 is a plunger 5 which is connected at its upper end to a table or pattern plate 6 and such plate extends over the top of the casing 2 and is of rectangular shape in an inverted cup-shaped form, so that its outer annular flange 7 will fit around the upper end of said casing when such plate is in its lowered position. Extending down from the pattern plate 6 is the inner annular flange 8, which is connected to the plunger 5 by a series of ribs or wings 9, while at each corner of the same and intermediate of said corners is a post or enlargement 10 extending around said flange from the bottom of the pattern plate 6 to a point below said flange. Below each of the enlargements 10 is a jarring post or bracket 11, which is formed as part of and extends inward from the inner face of the casing 2, and within each of the same is a seat 12 for the reception of a resilient jarring block 13, preferably formed of rubber or other suitable flexible material. Fitting within each of the seats 12 and against the upper faces of the blocks 13 therein, is a wearing block plate 14, and such plates extend above their respective seats and are adapted to come in contact with and be engaged by the lower ends of the posts or enlargements 10 in line with the same in the jarring operation of the machine.

Below the cylinder 3 in the casing 2 is another cylinder 15 which is located centrally of the walls of said casing and such cylinder has a piston 16 therein, such piston at its upper end being of a smaller diameter than the plunger 5 in the cylinder 3 while the lower end 17 of said piston is considerably greater in diameter than the plunger 15, the purpose of which will be hereinafter explained. The plunger 5 and the lower end 17 of the piston 16 are each provided with the usual packing rings 16' for preventing the leakage of the operating fluid from the cylinders 5 and 15 respectively and the cylinder 15 is inclosed at its lower end by a plate 18.

Along the outer side of the cylinders 5 and 15 is connected the valve casing 19 which has a fluid supply pipe 20 connected thereto and such pipe is adapted to enter said valve casing below a double faced valve 21, which, when raised, allows the compressed air or fluid from said pipe to enter the passageway 22 which communicates with a port 23 in the wall of the cylinder 5 so that the fluid from said pipe is adapted to enter said cylinder below the plunger 3 in order to raise the same in said cylinder. The upper face 24 of the double faced valve 21 is adapted to engage with a valve seat 25 when in its raised position and close a passageway 26 above the same which leads into an exhaust chamber 27, while said chamber is provided with an exhaust pipe 28 for carrying away the exhausted fluid from the machine.

Above the port 23 in the wall of the cylinder 3 is another port 29 which is closed by the plunger 5 in said cylinder except when the plunger has reached its upper position, and said port is adapted to communicate with a passageway 30 in the valve casing 19 while such passageway communicates with a small differential cylinder 31 at the upper end of the valve casing 19. This differential cylinder 31 contains a differential plunger 32 which has a recess 33 between the ends of the same and communicating with the recess at all times is a supply of compressed air or other operating fluid which enters said differential cylinder through the supply pipe 34 above the same.

The double faced valve 21 has a stem 35 connected to the upper end of the same and such stem extends upward into a small cylinder 36 and is connected to a piston 37 which operates in said cylinder simultaneously with said double faced valve. Above the cylinder 36 is an upper wall 38 which has a pair of ports 39 and 40 in the same and the former port is adapted to communicate with the cylinder 36 and with that portion of the differential cylinder 31 which is traversed by the recess 33 of the differential plunger 32, while the port 40 is adapted to extend between the cylinder 36 and that part of the differential cylinder 31 at the forward end of the differential plunger 32. The upper end of the differential cylinder 31 is provided with an exhaust opening 41 which is adapted to exhaust the fluid from the forward side of the differential plunger 32.

The plate 18 which incloses the lower end of the cylinder 15 is provided with a port 42 which is supplied with operating fluid from a pipe 43 and such pipe also takes care of the exhaust from the cylinder 15.

The plunger 5 has an opening 44 in the wall of the same and in line with the port 29 when said plunger is in its lower position and such port is adapted to convey the exhausted fluid from the passageway 30 and dif-

ferential cylinder 31 into the interior of said plunger where it is conveyed to the atmosphere through the port 45 at the upper end of the same into the casing 2, which has free communication with the atmosphere.

In the opposite side of the cylinder 3 from the valve casing 19 is a safety port 46 which is at a position slightly higher than the port 23 and said port leads into the interior of the casing 2 so that in case the ports in the valve casing 19 should fail to operate the fluid entering the cylinder 3 from the passageway 22 of said valve casing will be exhausted from said port 46 into said casing and pass from thence into the atmosphere.

At the bottom of the casing 2 and slightly above the base 1 is a shaft 47 which extends through said casing being journaled in the side walls of the same. This shaft 47 is provided at each end of the same and without the casing 2 with an upwardly extending rod or arm 48 and such arm is securely mounted on said shaft while at the upper end of the same is a plate or squeezing head 49. This squeezing head 49 extends between the arms 48 and is regulated in position by means of the nuts 50 which engage with the threaded outer end 51 of said arms so that the squeezing head 49 may be regulated or adjusted to any desired position on said arms.

On each side of the casing 2, where the shaft 47 emerges from the same, is a plate 52 which is bolted onto said casing and has an upwardly extending shoulder 53 and said shoulder has a heavy spiral spring 54 connected thereto in any suitable manner while the other end of said spring is connected securely to the arm 48 so that when the arms are in the position such as shown in Fig. 1 the spiral spring 54 will have considerable tension placed thereon and the operator can easily bring said squeezing head to a vertical position on account of the assistance rendered by said springs.

The top of the table or pattern plate 6 is so constructed by means of the resilient jarring device that anything laid on the top of the same will not be jarred out of position by the jarring operation as the force thus created is all exerted in a vertical direction. The top of the table is provided with a turnover plate 55, to which the pattern is conveniently secured by any suitable means, such as bolting, and the flask 56 is set in position on said turnover plate. This flask 56 is ordinarily of square shape and its size is regulated by the size of the pattern within the same, and said flask is open at both ends so that when placed in position the turnover plate 55 acts as a bottom for the same.

The turnover plate 55 is provided with a trunion body 55^a which has a bolt 57 extending downward through the hollow cen-

ter 58 thereof and such bolt is adapted to carry a trunnion 59 said trunnion being circular in cross-section and having threads in the same for engaging with the bolt 57. 5 Connected to the trunnion 59 and firmly secured thereto is a trunnion plate 60 which is adapted to limit the revolving of the turnover plate 55 as hereinafter described. The bolt 57, in the trunnion body 55^a is adapted 10 to be turned by means of the nut 61 at the top of the same and such turning of the bolt will change the position of the trunnion thereon, so that the exact center of gravity can be readily located in order to provide 15 for the easy rotation of the turnover plate 55 and the flask 56 carried thereon. The flask 56 at certain times is covered with a follow board 62 which when in position will be secured to the flask 56 by means of clamps 63 which unite the follow board, flask 56 and turnover plate 55 together so that the whole combination may be revolved without disturbing the contents of said flask, as hereinafter explained. 20

25 The casing is provided on two sides of the same with an arm 64 which is pivoted in said casing and has a forked end 65 and such end is also provided with a lug 66 on each side of the same, and each of said 30 lugs has a set screw 67 fitted into the same, said screws being freely rotatable in order to regulate the distance of the end of the same extending through said lug.

35 Connecting with each of the arms 64 is a rod 68 which engages at a point above the center of the same and such rod is connected at its lower end to a small arm 69, said connection being pivotal while the other end of said rod is connected to a shaft 70. The 40 shaft 70 is adapted to extend entirely through the casing 2 and the connection of the small arms 69 with the same is positive so that the revolving of said shaft will rotate said arms, and thus serve to operate 45 the rod 68 connecting with the arm 64. At one end of the shaft 70 is an operating handle 71 which is fixedly mounted on said shaft and said handle is operated by the operator of the machine at various times, as 50 hereinafter explained.

The use and operation of my improved molding machine is as follows: The turnover plate 55 is placed on the table or pattern plate 6 in such a position that the 55 trunnions 59 are centrally located on the vertical line of the machine and the pattern a is then secured to said turnover plate in any desired manner, such as by bolting after which the flask 56 is placed on said 60 turnover plate without any holding means and molding sand is then thrown into said flask and around the pattern a until the flask is heaped up with the same. The machine is now ready for operation. Com- 65 pressed air or other operating fluid is now

admitted to the valve casing 19 and such fluid enters from the main supply pipe 20 and passes upward past the valve 21 and into the passageway 22 whence it passes through the port 23 in the wall of the cylinder 3 and beneath the plunger 5. The plunger 5 is thus raised by the operating fluid until the bottom of the same passes the port 29 thereupon the operating fluid rushes through said port and passes up the 70 passageway 30 in the valve casing 19 and enters the differential cylinder 31 at the rear of the differential plunger 32 so that said plunger is thus moved over in said cylinder and the compressed air from the supply pipe 34 which enters the recess 33 in said differential plunger will thus connect or communicate with the port 39 in the upper wall 38 and pass downward into the cylinder 36 below the same. The forward end 75 of the differential cylinder 32 has closed the port 40 in the upper wall 38 so as to prevent the escape of the fluid through said port and as the said fluid enters the cylinder 36 it faces the piston 37 in said cylinder downward and thus shuts off the supply of compressed air or other operating fluid from under the plunger 5 so that said plunger 80 will fall in the cylinder 3 and the enlargements 10 will strike on the wearing block plates 14 and thus jar the contents of the flask so that the sand will be packed tightly around the pattern a and all crevices 85 and corners well filled with the same. As soon as the plunger 5 drops in the cylinder 3 the port 29 will thus be closed and the pressure on the differential plunger 32 will be stopped so that the plunger will return to its original position on account of the 90 fluid from the supply pipe 34 bearing 95 against the inner walls of said plunger of which the rear wall is of the greater diameter. As the plunger 5 drops in the cylinder 3 the fluid below the same will be exhausted from said cylinder through the port 23 in 100 the wall of the same and into the passageway 22, then through the passageway 26 above the same and into the exhaust chamber 27 from which it is exhausted through the exhaust pipe 28. The pressure of the 105 operating fluid in the main supply pipe 20 now raises the double faced valve 21 which carries with it the stem 35 and the piston 37 and the operation is repeated as described. After the jarring operation has been completed and the sand has all been packed around the pattern a with the required degree of solidity the admission of the operating fluid is cut off so that the plunger 5 will remain at its lower position in the cylinder 110 and the enlargements 10 on the pattern plate 6 will rest on the wearing block plates 14. The squeezing head 49 is now drawn upward by the operator so that the arms 48 115 of the same are in a vertical position and 120

125 of the same and into the exhaust pipe 28. The pressure of the operating fluid in the main supply pipe 20 now raises the double faced valve 21 which carries with it the stem 35 and the piston 37 and the operation is repeated as described. After the jarring operation has been completed and the sand has all been packed around the pattern a with the required degree of solidity the admission of the operating fluid is cut off so that the plunger 5 will remain at its lower position in the cylinder 130 and the enlargements 10 on the pattern plate 6 will rest on the wearing block plates 14. The squeezing head 49 is now drawn upward by the operator so that the arms 48 of the same are in a vertical position and 130

the said squeezing head will be adapted to be directly above the flask 56. Operating fluid is now admitted to the cylinder 15 through the supply pipe 43 and port 42 in the lower plate 18 of said cylinder and such fluid is of a very high pressure and moves the piston 16 upward until the upper end of the same reaches the bottom of the main plunger 5 in the cylinder 3 whereupon the said plunger is carried upward until the sand in the flask on the pattern plate or table 6 comes in contact with the squeezing head 49, so that the powerful pressure exerted will tend to squeeze the sand into said flask and thus increase the firmness and solidity of the same. The operating fluid is then exhausted from the cylinder 15 so that the plunger 5 and the piston 16 will assume their original positions, whereupon the squeezing head 49 is pushed back to its former position by the operator. The flask 56 is now cleaned of all superfluous sand above the upper ends of the walls of the same and the follow board 62 is placed thereon so that the said board completely covers the same. The turnover plate 55, flask 56 and follow board 62 are all united together by means of the clamps 63, which are easily adjusted and can be removed without any appreciable delay. The operating fluid is again admitted to the cylinder 15, as before described, so that the piston 16 and plunger 5 will be raised and the flask 56 thus elevated, after which the operator grasps the handle 71 and raises the same so that the small arm is moved downward, which will carry the rod 68 with the same so that the arm 64 will be revolved on its pivotal connection and this will cause it to assume a vertical position and the forked ends 65 of said arms will be directly beneath the trunnions 59 on the turnover plate 55. The operating fluid is now exhausted from the cylinder 15 through the port 42 and the supply pipe 43 so that the table or pattern plate 6 is lowered and the trunnions 59 rest in the forked ends 65 of the arms 64, while the said pattern plate will continue to drop until it assumes its original position with the enlargements or posts 10 resting on the wearing block plates 14. This will allow sufficient space for the flask to be revolved and this operation is easily accomplished by hand as the trunnions are so located as to be directly in the center of gravity of the flask. As the flask 56 is revolved the trunnion plate 60 limits its motion to half a revolution so that the said plate will strike and rest on the lug 66 on the forked end 65 of the arm 64. The operating fluid is again admitted to the cylinder 15 through the supply pipe 43 and port 42 in the lower plate 18 of said cylinder which will again raise the piston 15 and the plunger 5 so that the table or pattern plate

will rise to the position where the flask 56 rests upon the same. The clamps 63 are now removed from their engagement with the flask 56, follow board 62 and turnover plate 55, and said turnover plate having secured thereto the pattern a is resting on the top of the flask 56 while the follow board is between the pattern plate 6 and said flask. The operating fluid is now exhausted from the cylinder 15, as before described, and the pattern plate 6 is allowed to descend, while the flask 56 and follow board 62 resting upon the same will also descend on said plate and the pattern a, which is held by the turnover plate 55, will be withdrawn from the sand in said flask and will remain suspended on account of the engagement of the trunnions 59 of said turnover plate in the forked ends 65 of the arms 64. The flask 56 is now ready to have the molten metal poured into the same and is removed from the pattern plate 6 to any suitable location, while the turnover plate 55 will be removed from the upright forked arms 64 and another flask placed on the table 6 for a like jarring, squeezing and turning.

In the past the main disadvantage of jarring and squeezing machines has been the means of controlling the large cylinder necessary to give the tremendous power required in the squeezing operation. This difficulty has been removed by placing an independent cylinder in the machine for the sole purpose of squeezing the sand into the mold, and this cylinder is not connected in any way with the main plunger of the machine. By placing this independent cylinder below the main plunger a great amount of energy is saved in that if connected to said plunger it would be necessary to raise the same twenty or thirty times during the jarring operation.

The pattern drawing device requires no extra pneumatic appliances other than those already on the machine for other purposes.

Various modifications in the design and construction of my improved molding machine may be resorted to without departing from the spirit of the invention or sacrificing any of its advantages.

What I claim as my invention and desire to secure by Letters Patent is—

1. In a molding machine, the combination of a jarring table for carrying a pattern and flask, a plunger below said table for automatically jarring the same, a head for engaging with the top of said flask, and means below and independent of said plunger for pressing the sand in said flask against said head to squeeze said sand into said flask.

2. In a molding machine, the combination of a jarring table for carrying a pattern and flask, a plunger below said table for automatically jarring the same, a head for engaging with the top of said flask, and a

· piston below said plunger for pressing the sand in said flask against said head to squeeze said sand into said flask.

3. In a molding machine, the combination 5 of a jarring table for carrying a pattern and flask, a plunger below said table for automatically jarring the same, a pivoted head for engaging with the top of the flask and having a spring connected thereto, and 10 means below and independent of said plunger for pressing the sand in said flask against said head to squeeze said sand in said flask.

4. In a molding machine, the combination 15 of a jarring table for carrying a pattern and flask, a plunger below said table for automatically jarring the same, a pivoted head for engaging with the top of the flask and having a spring connected thereto, and a 20 piston below said plunger for pressing the sand in said flask against said head to squeeze said sand in said flask.

5. In a molding machine, the combination 25 of a jarring table for carrying a pattern and flask, a plunger below said table for automatically jarring the same, means below and independent of said plunger for raising said table and flask, and means engaging with the flask for suspending the same to 30 permit it to be turned for withdrawing the pattern from the same.

6. In a molding machine, the combination 35 of a jarring table for carrying a pattern and flask, a plunger below said table for automatically jarring the same, a piston below and independent of said plunger for raising said table and flask, and means engaging with the flask for suspending the same to 40 permit it to be turned for withdrawing the pattern from the same.

7. In a molding machine, the combination 45 of a jarring table for carrying a pattern and flask, a plunger below said table for automatically jarring the same, means below and independent of said plunger for raising said table and flask, means engaging with the flask for suspending the same to permit it to be turned for withdrawing the pattern from the same, and means on said last 50 named means and flask for limiting the movement of said flask.

8. In a molding machine, the combination 55 of a jarring table for carrying a pattern and flask, a plunger below said table for automatically jarring the same, a piston below and independent of said plunger for

raising said table and flask, means engaging with the flask for suspending the same to permit it to be turned for withdrawing the pattern from the same, and means on said last named means and flask for limiting the movement of said flask.

9. In a molding machine, the combination 60 of a jarring table for carrying a pattern and flask, a plunger below said table for automatically jarring the same, a head engaging with the top of the flask, means for pressing the sand in said flask against said head to squeeze said sand into said flask, and means engaging with the flask for suspending the same to permit it to be turned for withdrawing the pattern from the same.

10. In a molding machine, the combination 65 of a jarring table for carrying a pattern and flask, a plunger below said table for automatically jarring the same, a head 70 engaging with the top of the flask, a piston for pressing the sand in said flask against said head to squeeze said sand into said flask, and means engaging with the flask for suspending the same to permit it to be turned for withdrawing the pattern from the same.

11. In a molding machine, the combination 75 of a jarring table for carrying a pattern and flask, a plunger below said table for automatically jarring the same, a head 80 engaging with the top of the flask, means below said plunger for pressing the sand in said flask against said head to squeeze said sand into said flask, and means engaging with the flask for suspending the same to permit it to be turned for withdrawing the pattern from the same.

12. In a molding machine, the combination 85 of a jarring table for carrying a pattern and flask, a plunger below said table for automatically jarring the same, a head 90 engaging with the top of the flask, a piston below said plunger for pressing the sand in said flask against said head to squeeze said sand into said flask, and means engaging with the flask for suspending the same to permit it to be turned for withdrawing the pattern from the same.

In testimony whereof, I, the said ROBERT F. RINGLE, have hereunto set my hand.

ROBERT F. RINGLE.
